UNITED STATES PATENT OFFICE.

JOHN ALBERT BILLERMAN, OF BATTERSEA, LONDON, ENGLAND.

BUILDING CONSTRUCTION.

Application filed March 28, 1927, Serial No. 179,053, and in Great Britain November 13, 1925.

This invention relates to the construction of buildings and other structures of concrete slabs (armoured or not), and it has for its object to simplify and expedite their installation or erection whilst providing for good and permanent access or circulation of air for preventing condensation.

The type of construction to which the invention more particularly relates is that in which tongued and grooved slabs, panels, blocks, or the like, previously cast to the desired shape, are secured to concrete uprights or standards.

According to the invention, a wall construction comprises tongued and grooved slabs, panels, blocks, or the like, which are bonded to concrete uprights or standards and have the grooves in the upper edge formed with an auxiliary groove or channel 20 to receive means for securing or bonding them to the uprights. Further, concrete sills, on which rest the bottom course of slabs and the uprights or standards, are provided with continuous grooves, one of which 25 receives tenons on the uprights, and a smaller groove, which receives tongues on the slabs, and with air-ducts which allow air to enter from the outside and circulate within the wall. The upper ends of the uprights have 30 tenons which similarly engage a continuous groove in a concrete wall-plate.

The invention also comprises other features whereby the various parts of the construction are firmly secured together.

35 And in order that the invention may be readily understood, it will now be fully described with reference to the accompanying drawings, which show, by way of example, a building construction employing the new slabs or the like.

Figs. 1 and 2 are a cross section and a back view respectively of part of a wall constructed in accordance with the invention.

40 Fig. 3 shows a mode of supporting the wooden flooring joists, and

Fig. 4 shows the construction of a window sill.

Referring more particularly to Figs. 1 and 2,

45 *a* represents a concrete foundation sill formed of blocks of suitable length, *b* represents a facing slab, and *c* a recessed concrete standard or upright, both of which rest on the foundation sill *a*.

50 This foundation sill or bottom *a*, in its

turn, rests on a damp course *d* covering the ordinary foundation footing *e*.

f represents the tapering tenon or projection and *g* the groove by means of which the standards and sill are connected together, 60 the groove being, in this case, made almost as deep again as the projection to permit of a good filling or grouting to hold the parts together.

*f*¹ and *g*¹ represent tongues and grooves 65 or channels, which serve to connect the facing slabs or panels together, and to the foundation sill *a*.

h represents the additional channel or groove in the slab *b*, and *h*¹ the recesses in 70 the standards or uprights *c* into which engage the bent down ends of metal ties, dogs, or clamps *i*, which are embedded in cement mortar. The back of the recess *h*¹ in the face of the standard may be partly arched 75 or curved as shown, to facilitate the insertion of the tie, dog, or clamp. That portion of the standard *c*¹ in which the ties are held, is reinforced by an iron rod *c*², for the purpose of imparting greater strength to the 80 structure.

k is an air-duct, pocket, or opening, which extends downwards from the channel or groove *g* and then opens at the back of the foundation sill *a*.

85 In the arrangement shown in Fig. 3, for supporting the flooring joists, a wall-plate or beam *a*¹ is arranged between the top of one set of standards *c* and the bottom of the next set to form a bridge or bearing to support the ends of the wooden floor-joists *l*. These wall-plates or bearers are provided with reinforcement *m*, and also with air openings or ventilating ducts *h*¹.

As before, *b*, *c* represent facing slabs and *i* the ties or clamps for locking them to the standards.

The reinforcing rods *m*² in the standards may be allowed to project into the wall-plates or beams, as shown at *m*¹, to assist 100 in locking them together.

In the arrangement shown in Fig. 4, the window sill *a*² is provided with an additional groove or channel *n*¹, to receive the bottom flanges of the window frame *n*. The facing slabs and standards are indicated by the same letters as in the other figures, whilst *o* indicates the interior wall-lining and *p* a wooden moulding below the inside edge of the sill *a*².

The concrete standards may be cast in suitable sizes and lengths for convenient manipulation and to suit the work in view. They may also have tenons or lugs f at their top ends to fit into the sills or slabs a^2 .

Suitable air passages or ducts, like those shown in Fig. 2, are provided, where necessary, to allow entry of air between the outer wall of the structure and the finished lining, 10 which may be lath and plaster, or other suitable material.

The foundation footing e , may also be formed with air passages or ducts, below the damp course, to allow ventilation 15 throughout the structure, and to prevent condensation, as well as dry-rot in the wooden flooring and joists.

The wall-plates may be omitted, and a shoulder, or shoulders, may be cast on the 20 standards to receive the ends of the joists at the floor levels.

Having now described my invention what I claim is:—

1. A wall construction, including uprights, 25 slabs provided with tongues and grooves on the edges thereof, cooperating means in the upper edges of the slabs and in the uprights to bond the slabs to said uprights, said last means including a groove formed in

the upper edge of the slab, and a U-shaped 30 fastener having its terminals seated respectively in the groove on the slab and in the upright, said upright having a reinforced lip to receive one of said terminals of the fastener.

2. A wall construction, including a foundation, a sill mounted thereon and provided with an air duct and two continuous grooves, 35 said grooves being in its upper face, tongue and grooved uprights and slabs, each having its tongue fitted in the respective groove of the sill, and means for bonding the slabs to the uprights.

3. A wall construction, including a foundation, a sill mounted thereon and provided with an air duct and two continuous grooves, 40 said grooves being in its upper face, tongue and grooved uprights and slabs, each having its tongue fitted in the respective groove of the sill, and a plurality of U-shaped metal 45 fasteners adapted to be seated in the upper edge of its respective slab and into the body of the upright for attaching the slab to the upright.

In witness whereof, I have hereunto signed 50 my name.

JOHN ALBERT BILLERMAN.
